CLAIM

The ornamental design for a vehicle roll over protection device, as shown and described.

DESCRIPTION

FIG. 1 is a perspective view of the ROP device;
FIG. 2 is a top view of the ROP device;
FIG. 3 a front view of the ROP device;
FIG. 4 is rear view of the ROP device;
FIG. 5 is a right side view of the ROP device;
FIG. 6 is a left side view of the ROP device;
FIG. 7 is a bottom view of the ROP device; and,
FIG. 8 is a pictorial view of the ROP device as installed on
a vehicle, the vehicle shown in dashed lines as environmental
structure.
